UNITED STATES PATENT OFFICE.

ALEXANDER MARR, OF BROOKLANDS, NEAR MANCHESTER, ENGLAND.

APPARATUS FOR CLEANING TOBACCO-PIPES AND THE LIKE.

No. 902,752.

Specification of Letters Patent.

Patented Nov. 3, 1908.

Application filed July 27, 1906. Serial No. 327,975.

To all whom it may concern:

Be it known that I, ALEXANDER MARR, a subject of the King of Great Britain and Ireland, and a resident of Brooklands, near 5 Manchester, England, have invented a new and useful Improved Apparatus for Cleaning Tobacco-Pipes and the Like, of which the following is a specification.

My improvements relate to cleaning a tobacco pipe, cigar holder, cigarette holder or the like by drawing or exhausting through such a pipe or equivalent a continuous current of air under atmospheric pressure, or, similarly, a liquid or other fluid current, 15 which current will draw with it and discharge from the room or other place in which the operation takes place any accumulation of nicotin, moisture or other matters usually found in a pipe or the like after use. 20 The apparatus may be installed in tobacconists' or other shops, hotels, or other places of public resort and its use may be free to customers or users or a charge may be made.

If desired the apparatus may be brought 25 into action or be rendered operative by the insertion or payment of a coin, as, for example, in a penny in the slot machine.

The apparatus comprises a suitable continuous air exhausting device, preferably of 30 the jet exhauster type such as an ejector. Steam may be used for operating such ejector, but water under pressure from a town's supply will be found generally suitable, the water preferably only being turned 35 on when the apparatus is required for use. The air passage of the exhauster or ejector is connected to a suitable nozzle or other part in or upon which the bowl or other part of the pipe or the like (hereinafter referred to as a pipe) may be placed to form 40 a tight joint so that the air which is exhausted by the apparatus must pass through the pipe. When the water or other jet is turned on with the pipe in place the air is 45 sucked with great velocity through the pipe and the current of air carries with it any deposit in or from the pipe. The removed deposit passes through the ejector with the air and flows away with the water or other jet to a drain or suitable receptacle. 50

The accompanying drawings illustrate the construction of the apparatus provided with a water jet ejector and the application thereof to a tobacco pipe.

Figure 1 shows it in side elevation and Fig. 2 shows part of it in vertical section.

Figs. 3, 4 and 5 illustrate the combination with the existing device of a coin operated device which only permits the apparatus to be brought into action upon the prepayment 60 of a coin. Fig. 6 shows the combination with the apparatus of a receptacle for water and the method of using such water in cleaning a pipe. Fig. 7 is a cross sectional view of a form of self closing water valve 65 which may be used.

A is the inlet pipe of the water under pressure, B the ejector, and C the pipe through which the water, air, and matter removed from the tobacco pipe F pass to the 70 drain. E is a nozzle or cap communicating through the hold D with the air inlet D¹ of the ejector. The nozzle E is preferably formed of indiarubber or like flexible material and is preferably internally coned as 75 shown so that different dimensions and shapes of pipe bowls may make a tight sealed joint when pressed against it as shown in the drawing. When water is turned on so as to flow through the ejector 80 air is drawn with great velocity through the pipe stem and bowl F when properly in place as illustrated and through the openings D and D¹, and passes with the water and any matter removed from the pipe F 85 through the pipe C.

When the operation has continued for a sufficient length of time the pipe bowl is removed from the nozzle and the water is cut off.

The mouthpiece of the pipe may be removed for or during the operation if desired. Instead of the bowl of the pipe being pressed into the nozzle as shown, the mouthpiece or stem may be so pressed into 90 or upon an appropriate nozzle, but it is preferred to press the bowl as illustrated.

The nozzle E instead of being hollowed to receive the pipe bowl may be convex to enter therein as shown in Fig. 6, or it may be flat 100 with an elastic or flexible surface. Whatever form it may have I herein refer to it as a nozzle.

The valve for controlling the water supply may be operated independently, or it 105 may be opened or closed as a result of the pressure of the pipe bowl upon the nozzle and the removal of the pipe therefrom. This is shown in Fig. 1. The ejector and its connecting pieces are capable of slight movement. In this form G is the valve controlling the water supply, and is kept closed by 110

the pressure of a spring or by the water pressure. When the pipe bowl F is placed in the nozzle and pressure is exerted to make the required tight joint this pressure causes the 5 ejector and its attached parts to move and the stem G' of the valve is pressed against a fixed part H. By this pressure the valve is opened, the water flows and the ejector exhausts air through the pipe F. When the 10 tobacco pipe is removed from the nozzle and the pressure relieved, the ejector moves back to its original position by the springiness of its pipes or connections, or by other like means the pressure upon the valve stem G' 15 is released and the valve closes.

If desired any suitable liquid may be similarly passed or forced through by atmospheric pressure when the ejector is working, the mouthpiece of the pipe dripping into 20 a receptacle W for the purpose. Such liquid, when used, may be hot or cold, and, after the required quantity has passed through the pipe, air suction may be continued for some time to dry the pipe or 25 remove any moisture.

A suitable receptacle containing the liquid or a mixture thereof may be combined with or attached to the apparatus so that the stem or mouthpiece of the pipe under treatment may dip therein.

It is of course evident that other continuous air exhausting devices than an ejector may be used and be similarly combined with the nozzle in which the pipe is placed.

35 Figs. 3, 4, and 5 illustrate the combination with the exhausting device of a coin operative device which only permits the apparatus to be brought into use upon the prepayment of a coin. This coin operative device, 40 however, is not herein claimed. The coin operative device is contained within a suitable casing J provided with a slit or coin opening K through which the coin may be passed. Beneath this slit is a chute or receptacle L into which the inserted coin M 45 may pass and within which it stands upon edge upon the lower part as indicated in Fig. 3. In front of the coin, when in place in the chute, is an opening N in the latter through which the stem G' of the valve 50 may pass. The back of the chute is not straight but is beveled backwards for a distance approximately about equal to half the width of the coin. The coin M, until the 55 apparatus is brought into operation, is prevented from falling through an opening in

the lower end of the chute by a hinged counterweighted door O which normally closes such opening as shown in Fig. 3. With the coin properly in place as shown 60 in Fig. 3 and when the ejector is moved by the pressure of the pipe as before explained so that the stem of the valve presses against the face of the coin in the chute, the coin is tilted as indicated in Fig. 5 and becomes 65 rigidly held, and the door O is opened. Further pressure now opens the valve as the valve stem is now pressed against the rigidly held coin. When the pressure is released the coin falls downwards, (see 70 dotted lines Fig. 5) into a suitable receptacle, the door again closes under the influence of its counterweight P, the ejector and valve return to the positions shown in Fig. 3, as by the influence of the spring R, and the 75 apparatus is ready for another operation as soon as another coin is inserted. If no coin is in place the movement of the ejector does not open the valve as the valve stem freely passes into and through the openings N 80 and Q.

S is an arm attached to the door O and adapted to limit its opening movement by coming against the casing wall, or other fixed part.

I claim:—

1. Apparatus for cleaning a tobacco pipe by continuous suction, comprising in combination a water jet ejector air exhauster, a nozzle communicating with the air passage 90 thereof and so formed that the bowl or other part of the pipe may make an air-tight joint therewith, and a water supply control valve operable by pressure upon the nozzle, substantially as described.

2. Apparatus for cleaning a tobacco pipe by continuous suction, comprising in combination a water jet ejector air exhauster, a nozzle communicating with the air passage 100 thereof and so formed that the bowl or other part of the pipe may make an air-tight joint therewith, and a receptacle for cleansing liquid into which may dip the end of the pipe which is not applied to the nozzle, substantially as hereinbefore described.

In testimony whereof I have signed my name to this specification in the presence of two subscribing witnesses.

ALEXANDER MARR.
